UNITED STATES PATENT OFFICE.

URI HASKIN, OF PITTSBURG, PENNSYLVANIA.

GEARING FOR TRAINS OF METAL ROLLERS.

SPECIFICATION forming part of Letters Patent No. 269,574, dated December 26, 1882.

Application filed April 28, 1882. (No model.)

To all whom it may concern:

Be it known that I, URI HASKIN, a citizen of the United States, residing at Pittsburg, in the county of Allegheny and State of Pennsylvania, have invented a certain new and useful Improvement in Adjustable Differential Gearing for Continuous Trains; and I do hereby declare the following to be a full, clear, and exact description thereof, reference being had to the accompanying drawings, forming a part thereof, in which—

Figure 1 on Sheet 1 indicates a side elevation of my improved adjustable differential driving-gear, having a series of vertically-adjustable driving shafts and pinions mounted in open-top housings permanently attached to a single bed-plate, and provided with intermediate vertically and laterally adjustable idler shafts and pinions, which are mounted in laterally-adjustable open-top idler-housings, all of the housings being provided with breaking-caps in order to prevent injury to the more costly and less easily replaced portions of the machinery. Fig. 2 on Sheet 2 indicates a ground plan of the same. Fig. 3 on Sheet 3 indicates a front elevation of the same. Fig. 4 on Sheet 3 indicates an end view of one of the driving-spindles, with its spring-spreader in place. Fig. 5 on Sheet 3 indicates a side view of a section of the driving or coupling spindle, the spring-spreader, and a section of the coupling-box. Fig. 6 on Sheet 4 indicates a view of a central vertical section of one of the housings, showing the grooved inner surface of the same. Fig. 7 on Sheet 4 indicates a side view of the same. Fig. 8 on Sheet 4 indicates a plan view of one of the housings. Fig. 9 on Sheet 4 is a plan view of one of the breaking-caps. Fig. 10 on Sheet 4 indicates an end view of the same. Fig. 11 on Sheet 4 indicates an end view of one of the upper journal-boxes of the housing. Fig. 12 on Sheet 4 indicates a plan view of the same. Fig. 13 on Sheet 4 indicates a perspective view of the lower journal-box of one of the housings.

Like letters of reference indicate like parts wherever they occur.

My invention relates to a new and improved construction and arrangement for adjustable differential driving gear, and it is especially adapted for driving that class of continuous trains described and claimed by me in an ap-

plication recently filed, and for all other cases where long trains having from twelve to eighteen sets of rolls are used.

The continuous train consists of a series of sets of rolls mounted in housings provided with suitable means for adjusting each successive set to reduce the cross-section of the metal to the proper degree, and as the metal undergoes a degree of elongation at each pass proportionate to the degree of reduction of its cross-sectional area it is absolutely necessary that each successive set of rolls should be driven at a higher rate of speed than the set immediately preceding. This may be readily done by means of the driving-gearing heretofore in use; but, as each set of rolls must be driven at an exact and uniform rate, the efficiency of the continuous mill soon becomes seriously impaired by its liability to breakage, and to get out of working condition on account of the inability which has existed of keeping the driving-shafts in line with the axes of the rolls and of adjusting the driving mechanism from time to time to compensate for wear and different adjustments of the rolls, and consequently in time the driving-shafts get out of line, the pinions wear until they do not mesh properly into each other, the friction is increased, power is lost, the machinery loses its ability to run smoothly and jars, backlash takes place, and breakage of the train or its driving-gear results.

To the end, therefore, that the preceding difficulties may be overcome, and that the driving mechanism may be quickly, readily, and securely attached to the rolls and readily adjusted from time to time, to compensate for the wear or uneven wear of its boxes and pinions, I have devised an adjustable differential driving-gear in which the driving shafts and pinions are vertically adjustable, and are mounted in open-top housings which are permanently attached to a single bed piece, and the idler shafts and pinions are mounted in laterally-adjustable open-top housings, and are provided with means of vertical adjustment, all of the housings being provided with breaking-caps, and the driving-spindles being provided with a form of spreader which enables them to be quickly, readily, and securely attached to the rolls and driving mechanism. I shall now describe my invention more fully.

I shall now describe my invention more fully,

so that others skilled in the art may make and use the same.

In the drawings, Figure 1 represents a side elevation, and Fig. 2 a plan view, of my improved differential adjustable driving-gear, sufficient of the gearing only being shown to drive three sets of rolls, the remaining sets being driven by similar sections bolted and adjusted to the first.

10 A indicates a large cast-iron bed-plate, mounted on girders a and a' , and provided with a series of permanently-attached open-top driving-housings, A , A' , A'' , provided with vertical adjusting-screws a , a' , a'' , operating in threaded boxes at their lower part and against the lower surface of the lower journal-boxes of the driving-shafts, in order to adjust the driving-shafts and their pinions vertically from time to time to keep their axes in line with the 20 axes of the rolls.

15 B, B' , B'' and B''' , B''' indicate respectively the lower and upper journal-boxes of the driving-shafts. These boxes are provided with a vertical rib at each of their sides, in order that 25 they may be slipped down in position from above and be prevented from lateral displacement by means of their vertical ribs, which engage in vertical slots in the inner surface of the housings.

20 C, C' , C'' indicate the breaking-caps of the driving-housings, and are made sufficiently light to give way whenever any dangerous strain comes upon the train or driving mechanism, in order that breakage or serious injury to 35 the more costly and less easily replaced portions of the rolling and driving mechanism may be avoided. These breaking-caps are provided with central ribs, c , c' , and are slipped into position from below, and are held up against 40 the lower surface of the inwardly-projecting lugs at the top of the housings by means of the upper vertical tightening and adjusting screws, D , D' , which engage threaded bearings in them and operate upon the top journal-boxes of the driving-shafts.

45 D' and D'' indicate the intermediate detachable and laterally-adjustable idler-shaft housings. These housings are provided with breaking-caps, journal-boxes, and upper and lower 50 vertical adjusting-screws, constructed and arranged as specified in relation to the driving-shaft housings, all of the journal-boxes and breaking-caps being prevented from lateral displacement when slipped down and up, respectively, into position by means of their vertical ribs, which engage in vertical slots in the inner surface of the housings. These intermediate laterally-adjustable idler-shaft housings are hung or suspended in position between the 55 others by means of their laterally-projecting arms d , d' , which rest upon the upper ends of the driving-housings, and the arms d , d' are slotted in such a manner as to allow the lateral displacement of the idler-housings from time 60 to time, in order to readjust the idler-pinions to compensate for their wear.

d and d' indicate a set of lateral adjusting-screws attached to and operating in threaded boxes in the sides of each idler-shaft housing, and they also operate against the adjacent 70 sides of the driving-shaft housings.

By the use of the term "lateral adjustment," as applied to the idler shafts and pinions, I mean an adjustment in a line at a right angle with their axes, and as applied to the idler-shaft housings the adjustment effected by the adjusting-screws d and d' , which move the idler-housings fore or aft, when considered in relation to the rest of the driving mechanism. 75

80 E, E' , E'' indicate the driving-shafts, which are mounted in suitable bearings in the lower and upper journal-boxes of the fixed or driving housings, and are provided with suitable driving-pinions, E^3 , E^4 , E^5 , E^6 , which mesh into a series of idler-pinions, F^2 and F^3 , mounted 85 on the idler-shafts F and F' , all of these pinions being mounted and arranged on their respective shafts in the usual manner, to impart a higher and an exact rotary speed to each driving-shaft over the one immediately preceding 90 it.

In Figs. 4 and 5 on Sheet 3, E indicates the end of one of the driving-shafts.

95 G indicates a section of one of the coupling-boxes which are used to couple the driving-shafts to the roll or driving spindles. This coupling-box is constructed in the usual manner, except that the diameter of the coupling-opening increases slightly and gradually from points near the ends to the center of the box, 100 the object being to allow the couplings to wobble without bringing dangerous strains upon the continuous train and the driving-gear, if they should get out of line with each other, and this is accomplished by increasing the diameter of the opening toward the center of the box to allow of a slight vertical or lateral end-play of the parts within the box. 105

110 H indicates the form of spreader used to retain the position of the coupling-boxes upon the driving-shafts and roll-spindles. This form of spreader is produced by securing the spreader-blocks to a steel spring formed like a large section of a hoop. The objects of this construction chiefly are, first, to take advantage 115 of the elastic properties of the steel; to render the blocks self-adjusting, as they will be fixed and held in the grooves by the spring when it is slipped over the coupling-spindle; to render the coupling more secure and prevent the box 120 from slipping and throwing the coupling out of line; and, lastly, to enable all the driving-shafts to be more readily and quickly connected with or disconnected from the roll-spindles. 125

130 By reference to Sheet 4 it will be readily observed that the breaking-caps, upper and lower journal-boxes, and the inner faces of the housings or standards are constructed in a peculiar manner, the journal-boxes all being provided with projecting ribs at the center of their sides, adapted to engage and to admit of having a vertical movement in the central vertical slots

in the inner faces of the housings, the breaking-caps having a central rib on their upper surfaces, adapted to engage in vertical slots in the central portion of the inwardly-projecting lugs at the upper portion of the housings, and the housings being provided with central vertical grooves on their inner faces and through their lugs to receive the journal-boxes and the caps and allow their vertical adjustment.

10 The chief advantages of my improvement are as follows:

First. The driving-shafts may all be readily and quickly adjusted in line with the axes of the rolls.

15 Second. Any portion of the driving mechanism may be quickly thrown out of gear with the remainder without altering the position of the driving-shafts or throwing them out of line with the position the additional sets of rolls 20 will occupy when again placed in the train.

For instance, if but two sets of rolls in the train are to be used, the idler shaft and pinion which transmits motion from the second to the third driving-shaft is elevated, (after its top adjusting-screws are unloosed,) its top journal-boxes are removed, turned over, and placed on the lower boxes, thus serving as supports for the journals of the idler-shaft, and elevating it and the idler-pinion out of gear; and when additional sets of rolls are again to be driven, the entire driving mechanism is again thrown into gear by merely replacing the top boxes of the third idler-shaft in position, adjusting its breaking-cap, and screwing down its top adjusting-screw.

35 Third. The vertical and lateral adjustment of the idler-shafts compensate for the wear or uneven wear of the pinions, and they may be kept constantly meshing in the proper manner 40 with each other.

Fourth. The driving mechanism runs smoother, is subjected to less jars or shocks, requires less power, has less friction, develops less backlash, and is adapted to run longer trains than 45 any heretofore known to me.

Fifth. The peculiar form of the boxes and inner faces of the housings allow a quick insertion of the boxes into their place, their free vertical play, and avoidance of lateral displacement and end wear of the journal-boxes.

Sixth. Any serious strain will be taken up by—and cause the fracture of—the breaking-caps, thereby avoiding breakage of the more costly and less easily-replaced portions of the 55 rolling or driving mechanism.

Seventh. The driving mechanism is quickly and securely attached to and readily separated from the train.

In the description of my improvement I have 60 stated that the breaking-caps are all held up in position against the lower surface of the inwardly-projecting lugs at the upper portion of the housings by the upward pressure against them exerted by the upper tightening-screws; 65 but it is not necessary that they should be held in position by this means, as they may be

bolted to the lugs or held up against them by springs, or in other ways apparent to the skilled mechanic.

Having described my invention, what I claim, 70 and desire to secure by Letters Patent, is—

1. A differential driving-gearing for continuous trains, consisting of a series of vertically-adjustable driving shafts and pinions mounted in fixed housings, and provided with a series 75 of vertically-adjustable idler shafts and pinions mounted in laterally-adjustable idler-housings, whereby the driving-shafts may be readily adjusted in line with the axes of the rolls, and the idler-shafts adjusted vertically and laterally, to 80 compensate for the wear of the pinions, constructed and arranged to operate substantially as and for the purpose herein set forth.

2. A driving-gearing provided with intermediate laterally-adjustable idler-housings, 85 constructed and arranged to operate substantially as and for the purpose herein set forth.

3. An open-top housing provided with inwardly-projecting lugs at its upper ends, and having a detachable breaking-cap with ribs 90 which engage in grooves made in the upper portion of the housing, and held in position against the lower surface of the lugs by means of the vertical adjusting-screw, substantially as and for the purpose herein set forth.

4. An open-top housing provided with inwardly-projecting lugs at its upper ends, and having grooved inner faces, constructed and arranged substantially as and for the purpose herein set forth.

5. The combination of the open-top housing and its vertical adjusting-screws with the detachable breaking-cap and the vertically-adjustable journal boxes and bearings, substantially as and for the purpose herein set forth.

6. An open-top housing provided with a detachable breaking-cap, constructed and arranged substantially as herein set forth.

7. An idler-housing provided with laterally-projecting slotted arms adapted to rest upon 110 and be bolted to the upper end of the driving-housings, substantially as and for the purpose herein set forth.

8. An idler-housing provided with slotted arms *d d*, vertical adjusting-screws, and with 115 lateral adjusting-screws arranged between the adjacent faces of the fixed and movable housings, substantially as specified.

9. A driving-gearing provided with a series of vertically-adjustable driving shafts and pinions, and intermediate vertically and laterally adjustable idler shafts and pinions mounted in suitable housings or standards having detachable breaking-caps, constructed and arranged substantially as specified.

10. An adjustable differential driving-gear having adjustable driving shafts and pinions, vertically and laterally adjustable idler shafts and pinions, and self-adjusting steel spring spreaders, constructed and arranged to operate substantially as specified, whereby the driving-shafts may be quickly brought into

line with and connected to or disconnected from the train, and the idler-shafts adjusted to compensate for the adjustment of the driving-shafts and for the wear of the pinions.

5 11. A coupling-box having a coupling-opening which increases slightly and gradually in diameter from points near the ends to the center of the box, substantially as and for the purpose herein set forth.

12. An adjustable spring-spreader composed of two or more spreading-blocks riveted or secured to a section of steel hoop, substantially as herein set forth.

URI HASKIN.
